US00D390835S

United States Patent [19]

Mayfield, III

[11] Patent Number: Des. 390,835

[45] Date of Patent: **Feb. 17, 1998

[54] **CABINET FOR ELECTRONIC
COMPONENTS**

[75] Inventor: **John T. Mayfield, III**, Stone Mountain, Ga.

[73] Assignee: **Gichner Systems Group, Inc.**, Tucker, Ga.

[**] Term: **14 Years**

[21] Appl. No.: **61,155**

[22] Filed: **Oct. 16, 1996**

[51] LOC (6) Cl. **13-03**

[52] U.S. Cl. **D13/184**

[58] Field of Search **D13/184; D14/100,
D14/102; 312/263-265.5; 361/600-821;
174/35 MS, 35 R, 50-65 G, 65 R**
